[57] **ABSTRACT**

A transfer sheet, which may be a sheet of paper bearing a grease-impenetrable coating, is rubbed with a writing instrument, e.g., a wax-base crayon. The crayon-bearing surface of the transfer sheet is placed in opposition to a surface to be decorated and a rubbing pressure is applied to the opposed surfaces to transfer the crayon material to the surface to be decorated. The transfer sheet may rest on a textured surface while being rubbed by the crayon. A guide sheet for guiding the rubbing pressure may be placed over the surface to be decorated, and the transfer sheet placed between the guide sheet and surface to be decorated.

METHOD OF MAKING A DECORATIVE ARTICLE

This invention relates to decorating surfaces, and more particularly to a method of applying coloring matter in the form of a writing or drawing instrument, e.g., an ordinary wax-base crayon, to a surface.

In the description which follows, the writing instrument will be referred to as a crayon. However, it is to be understood that the writing instrument may be any implement, having the characteristics of a wax-base crayon, i.e., the capacity to be rubbed against the surface of a transfer sheet, as hereinafter described, to coat the latter with material which adheres to its surface without penetrating through, and which releases from the transfer sheet surface and is transferred to another surface upon applying a rubbing pressure between the transfer sheet and the other surface. In addition to wax-base crayons, implements such as so-called grease pencils, and those having a certain type of plastic or synthetic base have been used successfully.

Conventionally, crayon coloring is performed by rubbing a crayon stick directly against the surface to be decorated.

It is an object of the present invention to provide a method of applying crayon coloring matter to a surface by transferring the crayon material from a transfer sheet to which the crayon material has first been applied.

Generally speaking, the method of this invention involves rubbing a surface of the transfer sheet with a wax-base crayon, placing the crayon-bearing surface of the transfer sheet in opposed relation to the surface to be decorated, and rubbing either the transfer sheet or the rear face of the surface to be decorated to cause the crayon to be released from the transfer sheet and applied to the surface to be decorated. Transfer of the crayon in this way takes place only in the area to which the rubbing pressure has been applied.

Among the advantages offered by the present invention are the following:

1. There is greater control of application of the crayon to the surface to be decorated. Thus, with an ordinary crayon stick only relatively thick lines or blocks of color can be applied. With the present invention, pressure can be applied between the crayon-bearing surface of the transfer sheet and the surface to be decorated with a pointed tool. In this way, distinct borders of crayon colored areas can be achieved, and very thin crayon lines can be drawn.

2. Crayon coloring can rapidly be applied to the surface to be decorated in an unlimited number of patterns. If the transfer sheet is rested on a textured surface while the crayon is applied to it, application of the crayon will be in a pattern conforming to the texture. The crayon is thereafter transferred to the surface to be decorated in the same pattern.

3. Crayon colors can be overlapped on the surface to be decorated without having the colors blend into one another, as happens when a crayon stick of one color is rubbed over crayon material of another color previously applied to the surface to be decorated. With the present transfer method, subsequently applied crayon material lies right on top of previously applied crayon material.

A feature of the invention is the use of a guide sheet adapted to be laid over the surface to be decorated, bearing an illustration divided into a number of dis-

crete areas. Each area bears some indicia indicating, for example, which color and/or texture should be used to color the corresponding area of the surface to be decorated. A transfer sheet to which a particular color and/or texture has been applied is placed between the guide sheet and surface to be decorated, and the rubbing pressure is applied to the particular area of the guide sheet corresponding to the color and/or texture on the transfer sheet. In this way, the user is guided in producing a composite illustration of different colors and textures.

Additional features and advantages of the invention will be apparent from the following description in which reference is made to the accompanying drawings.

In the drawings:

FIG. 1 is a perspective view of the items which may be provided to carry out the present method;

FIG. 2 is a perspective view illustrating the application of crayon to a transfer sheet;

FIG. 3 is a perspective view showing a crayon-bearing transfer sheet being rubbed, through a guide sheet, against a sheet to be decorated;

FIG. 4 is a fragmentary perspective view of the sheet to be decorated after the transfer of crayon material to it;

FIG. 5 is a fragmentary cross-sectional view on an enlarged scale, taken along line 5-5 of FIG. 3;

FIG. 6 is a fragmentary cross-sectional view showing a crayon being rubbed on a transfer sheet while the latter rests on a resilient surface;

FIG. 7 is a fragmentary cross-sectional view showing a crayon being rubbed on a transfer sheet while the latter rests on a textured surface; and

FIG. 8 is a view similar to FIG. 4 showing the sheet to be decorated after application of textured crayon pattern to it.

The procedure chosen to illustrate the present invention may be carried out with the items shown in FIG.

1. In the present example, the surface to be decorated is the upper face 10 of a piece of relatively stiff and heavy cardboard 11. However, the surface to be decorated can be any surface capable of accepting crayon. Overlying the board 11 is a guide sheet 12, preferably formed of a transparent material such as acetate. The guide sheet need not necessarily be transparent; it could be translucent, such as a sheet of tracing paper, or even opaque. The guide sheet, however, must be thin enough so that pressure applied to its upper surface is transmitted through to the surface 10 beneath.

Guide sheet 12 carries an illustration 13, in the present embodiment a picture of a fish, at a location wherein it can be seen by the user. The illustration 13 is divided into several discrete areas, each area bearing a numeral, in this case the numerals 1-6 are used. The numerals are keyed to a color chart (not shown) or to numerals on the crayon sticks 14, to indicate to the user the suggested color for each area of the picture, i.e., for each area of surface 10 underlying each area of the illustration 13. Obviously, indicia other than numerals may be employed to accomplish this purpose. If desired, additional encircled numerals, such as the numeral 7 in the area bearing the numeral 3 may be employed to indicate a second color and/or texture to be applied to the corresponding area of surface 10 after the first color is applied thereto. Preferably, means

such as a suitable adhesive along edge 15 secures guide sheet 12 to board 11 to maintain registry between the two during use.

FIG. 1 also illustrates a number of transfer sheets 18 which are initially blank, i.e., bearing no crayon material. These sheets may be any sheet material having a surface which accepts grease or wax without permitting the grease or wax to penetrate through the surface. Paper of the type used to wrap butter has been used successfully. This is parchment paper provided with a grease-resistant surface coating.

A resilient pad 19, such as a thin sheet of foam rubber or foam plastic covered by a smooth plastic layer, has been found useful under some circumstances when it is desired to apply a solid over-all crayon coloring to a transfer sheet. In such a case, the transfer sheet is rested on pad 19 (FIG. 6) while a crayon is rubbed over its surface. Under some conditions, simply resting the transfer sheet on a hard smooth surface (FIG. 2) while rubbing a crayon over it yields satisfactory results.

A block 20 having different surface textures is also shown in FIG. 1. In the present example, the surface of one half 21 of block 20 has a window screen texture, and the surface of the other half 22 has a pebbled texture. It will be appreciated that if a transfer sheet 18 is rested on the surface of block part 21 (FIG. 7) and its surface is rubbed with a crayon 14, the crayon material is applied to the surface of the transfer sheet in a window screen pattern. Thus, literally any textured surface may be used as a base for supporting a transfer sheet 18 while the latter is rubbed by a crayon 14, and the crayon material will be applied to the transfer sheet in the pattern of the texture of the base. As another example, resting a transfer sheet on a piece of leather causes the crayon to be applied in the pattern of the leather grain.

A tool 25 having a handle 26 and a rigid working end 27 is provided for applying rubbing pressure to transfer crayon material from the transfer sheet to the surface 10. Crayons 14 may be conventional wax-base crayons.

In use, a transfer sheet 18 is placed on a flat hard surface (FIG. 2) or a resilient surface (FIG. 6), a crayon 14 of appropriate color is selected, and the surface of the transfer sheet 18 is rubbed to apply a layer of crayon material 29 to the surface of the transfer sheet. The hard flat surface or resilient surface are used when a solid area of color is desired on the transfer sheet. If a pattern of crayon material 30 (FIG. 7) is desired, the transfer sheet is rested on a textured surface.

The transfer sheet 18 is then placed between the board 11 and guide sheet 12 (FIG. 3) with its crayon-bearing face in opposed relation to the surface 10 to be decorated. One of the areas of the illustration 13 carried by the guide sheet 12 is then rubbed by means of the tool 25 (see FIGS. 3 and 5). In FIG. 3, the area labeled with the numeral 6, and representing one fin of the fish, is shown being rubbed by the rigid end 27 of the tool. If the color selection system mentioned above is being used, the transfer sheet will have been rubbed with a crayon 14 of the color corresponding to numeral 6. Rubbing of the guide sheet area 6 with tool 25 applies a rubbing pressure between the surface 10, and the crayon-bearing surface of the transfer sheet, whereupon the crayon material 31 (FIG. 4) in the shape of a fish fin is released from the transfer sheet and applied to the surface 10 of board 11. If the transfer sheet had been rested on the portion 22 of texture block 20 while

being rubbed with a crayon, overall rubbing of area 6 of the guide sheet would have resulted in transfer of crayon material 32 (FIG. 8) in a pattern.

In the case of an area such as the area bearing numeral 3, a transfer sheet carrying solid or patterned crayon material may be used first, and the area 3 rubbed with tool 25, and thereafter a transfer sheet bearing a pattern of crayon material which may be identified by numeral 7, preferably a color different from the color used first, is used and the area 3 is rubbed again. As a result an overlying pattern of color is applied to the first crayon material transferred to surface 10 in the area 3. If desired, the same area 3 can be rubbed again with a third transfer sheet bearing yet a different pattern and color. As a result of transfers of crayon by rubbing of all the areas of illustration 13, a composite picture of a fish, made up of different colors and patterns, is applied to surface 10. After completion of the illustration on surface 10, guide sheet 12 is removed.

It should be pointed out that the variety of decoration applied to a surface to be decorated by the present invention is virtually infinite. There is a wide choice of colors which can be used, and an even wider choice of textures. Furthermore, an entire area can be rubbed with a tool, such as tool 25, to transfer all the crayon material carried by the transfer sheet in that area to the surface to be decorated, or a pointed tool can be used to selectively apply pressure in an area, whereby a design comprising very thin crayon lines is applied to the surface to be decorated.

A modified way of practicing the invention should be mentioned, in which the lower face of guide sheet 12 is the surface to be decorated. Accordingly, a transfer sheet 18 is placed beneath the guide sheet with the crayon-bearing surface of the transfer sheet facing the lower face of the guide sheet. In this case, the board 11 is eliminated, and the lower face of the transfer sheet rests on a support surface. When rubbing pressure is applied to the upper face of the guide sheet, the crayon material 29 or 30 is transferred to the lower face of the guide sheet. If the guide sheet is transparent, the crayon can be viewed through the upper face of the sheet.

It should also be mentioned that since the crayon material is completely released from the transfer sheet 18, the sheet can be reused. Thus, the same transfer sheet can be used, at different times, to transfer different colors and/or different patterns of crayon to the surface to be decorated.

The invention has been shown and described in preferred form only, and by way of example, and many variations may be made in the invention which will still be comprised within its spirit. It is understood, therefore, that the invention is not limited to any specific form or embodiment except insofar as such limitations are included in the appended claims.

What is claimed is:

1. A method of making a decorative article comprising the steps of
  - a. providing an article having a surface to be decorated,
  - b. providing a transfer sheet having a surface which accepts a wax-like or grease-like coating without permitting such coating to penetrate through the surface,
  - c. rubbing said surface of the transfer sheet with a writing instrument having the characteristics of a

- wax-base crayon while the transfer sheet rests on a textured surface, whereby the crayon-like material is applied to the transfer sheet in a pattern conforming to that of the textured surface,
- d. placing the crayon-bearing surface of the transfer sheet in opposition to the surface to be decorated, and
- e. applying a rubbing pressure to an area of said opposed surfaces,
- whereby the crayon material carried by the transfer sheet in the rubbed area is transferred to the surface to be decorated in the pattern conforming to that of the textured surface.
2. A method as defined in claim 1 wherein the rubbing pressure is applied by rubbing the surface of the transfer sheet opposite the crayon-bearing surface.
3. A method as defined in claim 1 wherein the article is a piece of sheet material, and the rubbing pressure is applied by rubbing the surface of the sheet material opposite the surface to be decorated.
4. A method as defined in claim 1 wherein the rubbing pressure is applied by rubbing the transfer sheet or the article with a rigid tool.
5. A method as defined in claim 1 including the step of resting the transfer sheet on a resilient base while rubbing its surface with the writing instrument.
6. A method as defined in claim 1 including the step of transferring crayon-like material from the transfer sheet to an area of the surface to be decorated which

10

15

20

30

35

40

45

50

55

60

65

has previously received crayon-like material from a transfer sheet.

7. A method as defined in claim 6 wherein the subsequent transfer is of crayon-like material carried by the transfer sheet in a textured pattern.

8. A method as defined in claim 1 wherein said transfer sheet is a paper sheet at least one surface of which bears a grease-impenetrable coating.

9. A method as defined in claim 1 including the steps of

f. providing a guide sheet bearing an illustration having a plurality of discrete areas,

g. placing the transfer sheet between the guide sheet and the surface to be decorated with the surface of the transfer sheet bearing the crayon-like material in contact with the surface to be decorated, and

h. rubbing the exposed surface of the guide sheet within one of the discrete areas,

whereby different areas may be rubbed when different transfer sheets are used to create a composite illustration on the surface to be decorated.

10. A method as defined in claim 9 wherein the guide sheet bears indicia in the discrete areas indicating the particular type of crayon-bearing transfer sheet to be used when each area is rubbed.

11. A method as defined in claim 9 wherein the guide sheet is transparent.
